[57] CLAIM

The ornamental design for a combined headlight ring and visor for a motorcycle, as shown and described.

DESCRIPTION

FIG. 1 is a perspective view depicting the combined headlight ring and visor for motorcycle according to the invention;

FIG. 2 is a front view depicting the combined headlight ring and visor for motorcycle according to the invention;

FIG. 3 is a side elevation view of the combined headlight ring and visor for motorcycle of FIGS. 1 and 2;

FIG. 4 is a top view of the combined headlight ring and visor for motorcycle of FIGS. 1, 2 and 3;

FIG. 5 is a rear view of the combined headlight ring and visor for motorcycle;

FIG. 6 is a bottom view of the combined headlight ring and visor for motorcycle; and,

FIG. 7 is a perspective view of a second embodiment of the combined headlight ring and visor for motorcycle.

The rear of the second embodiment of the design is substantially similar to the rear view shown in FIG. 5.
